Filed Oct. 5, 1970, Ser. No. 25,336

Term of patent 14 years

Int. Cl. D7—01

U.S. Cl. D36—8

FIG. 1 is an elevational view of a tumbler or similar article showing my new design;

FIG. 2 is an elevational view rotated 90 degrees from the view in FIG. 1;

FIG. 3 is an elevational view rotated 90 degrees from the view in FIG. 2;

FIG. 4 is an elevational view rotated 90 degrees from the view in FIG. 3;

FIG. 5 is a developed elevational view of the ornamentation; and

FIG. 6 is a top plan view of the tumbler.

The characteristic feature of my design resides in the specific ornamentation as applied to a typical tumbler.

I claim:

The ornamental design for a tumbler or similar article, substantially as shown and described.
